[57] CLAIM

The ornamental design for a speaker, as shown and described.

DESCRIPTION

FIG. 1 is a front, right perspective view of the speaker showing our new design;

FIG. 2 is a front view thereof;

FIG. 3 is a right side elevational view thereof, the left side view being a mirror image;

FIG. 4 is a rear view thereof, the phantom line structure forming no part of the invention;

FIG. 5 is a top plan view thereof;

FIG. 6 is a bottom plan view thereof; and,

FIG. 7 is a partial sectional view of the front thereof along line 7—7 in FIG. 2.
